UNITED STATES PATENT OFFICE

2,447,766

DRIER

John C. Monick, Longview, Wash.

Application March 7, 1947, Serial No. 733,169

2 Claims. (CL. 34—231)

1

This invention relates to driers, and more particularly to such driers as may be electrically heated and ventilated for the purpose of drying and aerating articles of laundry including babies' diapers.

An object of this invention is to provide a drier in which the danger of scorching or burning the article to be dried is reduced to a minimum.

A further object is to provide a drier in which the dried article may be aerated.

A further object is to provide a drier in which the danger of discoloration of the articles undergoing the drying process, by corrosion of the support on which they are suspended, is reduced to a minimum.

A further object is to provide a drier in which fresh air is forced, heated and uniformly circulated substantially throughout the drier and then exhausted to the outer atmosphere.

A further object is to provide automatic control of the temperature within the drier.

A further object is to provide a portable drier of inexpensive, simple construction having a minimum of parts contained within an enclosing cabinet which may be readily moved to any suitable location when desired for use, or readily stowed when not in use.

The above and still further objects of this invention, as well as its construction, arrangement and operation, will become apparent from the following description when taken in conjunction with the accompanying drawings, the invention being particularly pointed out in the appended claims.

Reference is made to the drawings wherein like numerals of reference apply to the same parts throughout the several views, and wherein:

Figure 1 is a front elevation, partly in section, of the drier,

Figure 2 is a plan view of the drier partly in section,

Figure 3 is a sectional elevation taken along line 3—3 of Figure 1, looking toward the air inlet end of the drier,

Figure 4 is a sectional elevation taken along line 4—4 of Figure 1, looking toward the opposite end of the drier from the air outlet,

Figure 5 is an elevational view of the air inlet end of the drier, and

Figure 6 is a perspective view of an air deflector used within the drier.

Referring to the drawings in detail, a portable cabinet comprising a front 10, rear 11, ends 12 and 13 and bottom 14, of any suitable material

2

cut and bent to desired shape and welded, riveted or otherwise secured together, is provided with a lid or cover 15 adapted for raising on hinges 16 and containing a screened exhaust port 15a, a handle 17 and legs 18, forming a suitable enclosure wherein may be located the various devices for supporting articles to be dried and aerated and the equipment installed to complete the drying and aerating operations.

10 Near the top of the cabinet and longitudinally disposed therein are a plurality of spaced rods 19 of any suitable shape and composed of non-corroding material. These rods are supported by means of end brackets 20 which are secured in any suitable manner to the ends of the cabinet. The articles to be dried or aerated may be hung or otherwise supported from these rods, as shown in Figures 1 and 4, where articles 21 and 22 of different sizes are indicated.

20 A plurality of angular frame supports 23 secured by means of bolted brackets 25 to the walls 10 and 11 of the cabinet have drip pans 26 welded or otherwise secured to them. These pans are provided for the purpose of catching 25 any excess moisture dripping from the articles to be dried. These drippings may be discarded in any suitable manner, such as, for example, connecting with a drainage system. The location 30 of the heater units 27 beneath and protected by the drip pans 26 also serve to prevent the drippings from contacting the heater units, and thus being converted into steam to retard the drying process. These drip pans also serve 35 the purpose of shielding the drippings from the main force of the air stream and thus serve to prevent their being re-deposited on the drying articles by the force of the air stream.

Positioned beneath and preferably supported 40 by means of brackets 25 are a plurality of electrical heater units 27 to heat the air within the cabinet.

At one end of and preferably within the cabinet an electrically driven fan 28 is located adjacent 45 a suitable screened opening or aperture 29 for the purpose of forcing fresh air into the interior, and thus accelerating the drying operation.

Air deflectors 30, 31, 32 and 33 are supported by means of the frame brackets 25 and are suitably proportioned and disposed to assure a uniform distribution of the air from fan 28, throughout the interior of the cabinet, until exhausted through screened exhaust port 15a in the hinged cover.

55 The air deflectors, shown in detail in Figure 6,

consist of an arcuate scoop portion 32a provided at its top with an integral bracket formed by bending a portion 34 thereof longitudinally at right angles to the scoop 32a and then bending the ends 35 and 36 upward at right angles to form a supporting bracket for suitable attachment to the side walls of the cabinet or to bracket 25 by providing bolt holes in either end 35 and 36 or flat portion 34, or both.

It will be readily understood that frames 23, drip pans 26, heat units 27 and air deflectors 30, 31, 32 and 33 may be assembled as a complete unit prior to installation within the cabinet.

On one end of the cabinet, preferably on the inside of end 13 where the fan is located, control switches 37 and 38 are installed for separate control of the fan motor 28 and heater unit 27, respectively. The manipulating knobs or handles of these switches may extend through the cabinet wall to the outside for ease of operation. These switches 37 and 38 may also embody a variable control, such as, for example, a rheostat, in order that various degrees of heat may be obtained from the heating units 27 and for varying the speed of the fan 28, as desired or required. A thermostat 39 may also be secured to the inside of the cabinet end 13. The electrical equipment herein described may be connected and correlated in an electrical system of conventional design for full automatic control to maintain any predetermined condition of heat and air circulation within the cabinet and arranged to prevent charring or burning of the articles in the event of failure of the fan to properly operate. An extension cord and plug 40 is provided for connection to any suitable source of electrical power.

It will be understood that in addition to drying the articles placed within the drier, such articles can also be aerated by turning off the current to the heating units 27 and running the fan 28 at sufficiently high speed to cause the dried articles to become soft and fluffy.

It is to be understood that various modifications and changes may be made in this invention without departing from the spirit and scope thereof, as set forth in the appended claims.

What is claimed is:

1. In a drier, an open topped cabinet having side and end walls, a cover hingedly mounted over the open top of said cabinet and having an open-

ing therein, a plurality of spaced, parallel horizontally disposed rods positioned within said cabinet adjacent the top thereof and supported by the end walls of the cabinet for supporting articles to be dried, a plurality of spaced frame supports disposed below said rods and secured to the side walls of said cabinet, a plurality of pans arranged longitudinally in said cabinet and supported on said frame for collecting water from the articles being dried, heater units disposed below said drip pans and supported in said cabinet, there being an aperture in one of said end walls for the ingress therethrough of air, and a fan positioned contiguous to said aperture for circulating air through said cabinet and out through the opening in said cover.

2. In a drier, an open topped cabinet having side and end walls, a cover provided with an opening hingedly mounted over the open top of said cabinet, a plurality of spaced parallel horizontally disposed rods positioned within said cabinet adjacent the top thereof and supported by the end walls on the cabinet for supporting articles to be dried, a plurality of spaced frame supports disposed below said rods and secured to the side walls of said cabinet, a plurality of pans arranged longitudinally in said cabinet and supported on said frame supports for collecting water from the articles being dried, heater units disposed below said drip pans and supported in said cabinet, there being an aperture in one of said end walls for the ingress therethrough of air, a fan positioned contiguous to said aperture for circulating said air through said cabinet and out through the opening in said cover, and a plurality of spaced air deflectors arranged below said drip pans and dependently supported in said cabinet.

JOHN C. MONICK.
